UNITED STATES PATENT OFFICE.

GEORGE SHERMAN CLARK, OF HUNTINGTON, WEST VIRGINIA, ASSIGNOR TO CLARK
PATENT TUBING CO., OF WHEELING, WEST VIRGINIA, A CORPORATION OF WEST
VIRGINIA.

TUBE-WINDING MACHINE.

Application filed November 3, 1921. Serial No. 512,488.

In the industrial arts tubes formed from strips or ribbons of paper and analogous cheap and flexible material are meeting with a demand, particularly in the mining industry, where explosive cartridges are required for loosening strata and removing obstructions.

The present invention provides a machine which takes flexible strip material, such as these blasting tubes, forms the tube or other material into a package of predetermined size, severs the tube and delivers it, all in one cycle of operation, the several steps being entirely automatic.

While the drawings illustrate a preferred embodiment of the invention, as particularly applied to the packaging of blasting tubes, it will be understood that the invention is not limited to the form shown but may be otherwise embodied or applied to the packaging of other material without departing from the nature of the invention.

In the accompanying drawings illustrating the present preferred embodiment of the invention—

Figure 1 is a side elevation of a machine embodying my invention and showing the manner of feeding strip material thereto;

Figure 2 is a top plan view, to enlarged scale, of the packaging apparatus shown at the left hand part of Figure 1;

Figure 3 is a side elevation of the apparatus shown in Figure 2;

Figure 4 is an end view of the same;

Figure 5 is a vertical section on the line 5—5 of Figure 2;

Figure 6 is a vertical section on the line VI—VI of Figure 5;

Figure 7 is a vertical section on the line VII—VII of Figure 2;

Figure 8 is a vertical section on the line VIII—VIII of Figure 2;

Figure 9 is a section on the line IX—IX of Figure 4;

Figure 10 is a detail view showing the mechanism for throwing the ejecting mechanism out of action;

Figure 11 is a partial view showing the clutch employed for controlling the supply means, and

Figure 12 is a partial view showing the manner of controlling the shearing mechanism.

Corresponding and like parts are referred to in the following description and designated in the several views of the drawings by like reference characters.

The operating mechanism is mounted upon a suitable framework which, in the present instance, is shown as comprising a base 1 and a table 4. Suitable uprights connect the table with the base 1 and may be braced and stayed in any determinate way. A motor 5, preferably of the electric type, is provided for operating the working parts. For convenience, the motor 5 is mounted upon the framework. A countershaft 6, mounted upon the framework, receives motion direct from the motor 5 by means of a drive belt 7. A transverse shaft 8 derives motion from the countershaft 6 by means of a drive belt 9.

A plurality of pairs of compressing and feed rolls are mounted upon the table 4 and are designated by the letters A, B and C, respectively. These pairs of rolls are mounted alike, the rolls of each pair being relatively adjustable. Each pair of rolls is mounted in standards 10, which are vertically slotted, as indicated at 11, to receive bearings 12 and 13, the bearing 12 being adjustable by means of a set screw 14, which is threaded into the upper end of the standard 10. The rolls are preferably hollow and are mounted upon shafts 15 which project and are connected at corresponding ends by means of spur gearing 16. A drive chain 51 connects a sprocket 51^a driven from the shaft 8 with the lower roll of the pair A, thus driving the feed rolls at suitable speed. A drive chain 17 connects corresponding rolls of the pairs A and B. A drive chain 18 connects corresponding rolls of the pairs B and C. A drive belt 19 connects one of the rolls of the pair C with the tube forming mechanism (not shown) supplying the packaging machine forming the present invention.

It should be stated that the machine may be of any capacity with reference to the number of tubes packaged at the same time. The machine illustrated is adapted to package two tubes at a single operation, and one mechanism is a duplicate of the other, hence a detailed description of one will suffice for a clear understanding of both, and the num-

ber of mechanisms may vary according to the required output of the machine as a whole. Tubing or other material to be packaged may be supplied from any desired source (not shown). The machine is particularly illustrated for the packaging of blasting tubes and at the right hand side of Figure 1 is shown a mechanism 20 receiving tubing 21 and a damp sealing strip 22, the mechanism 20 being effective for pressing the sealing strip against the tubing to produce a sealed blasting tube 21^a. This tube is fed through the rolls C, B and A, thus firmly compressing the tube, insuring the adherence of the sealing strip to the tube body, and finally supplying the tube to the packaging mechanism which will now be described in detail.

A transverse shaft 47, paralleling the shaft 8, derives motion therefrom through the instrumentality of a shaft 48, bevel-gearing 49 between the shafts 8 and 48, and worm gearing 50 between the shafts 47 and 48. Drums 52, 53 and 54 are fast to the shaft 47 and rotate therewith. The drums 52 and 54 are provided with cams 52^a and 54^a, respectively, which are set one in advance of the other. A lever 55, pivoted intermediate its ends, cooperates with the cams of the respective drums 52 and 54. The two ejector mechanisms are complementary duplicates of each other and a description of one will serve to explain the operation of each. A shaft 56 is provided with a sleeve 56^a, and this sleeve has a sprocket 57 loosely mounted thereon. The sprocket 57 drives the sleeve 56^a through a spring 56^b, thus providing a slip gear drive. A drive chain 58 connects the sprocket 57 with a companion sprocket 57' fast to the shaft 8. A clutch member 59, rotatable with the shaft 56 and movable longitudinally thereon, is in clutch engagement with the sleeve 56^a and is normally held in operative position by means of an expandable helical spring 60 mounted on the outer portion of the shaft 56. The lever 55 engages the clutch member 59 and when actuated by the cooperating cam 52^a or 54^a disengages the clutch member 59 from the sprocket 57, and at this time the tube is severed and the package ejected. The shaft 56 is provided at its inner end with a head 61 from which project pins 62. The tube is wrapped about the pins 62 to form a package of predetermined size. After the package has been wound to substantially the desired size the tubing is severed, but the winding heads continue their rotation to cause winding of the severed end portion. If desired, the operator may place his hand on the rotating package at this time and when the winding has been finished manually attach a sticker to prevent unwrapping. The finished package is discharged by means of an ejector or stripper

63 which is slidable on the pins 62 and strips the package therefrom. In its delivery, the package passes through an opening 64 formed in the table 4.

The periphery of the ejector or stripper 63 is formed with an annular groove in which is fitted a strap 65. Guide members 66 and 67 slidably support crossheads 68, each having connection with the respective straps 65. Each crosshead 68 is provided with a projection 69 disposed to cooperate with cams 71 and 72 mounted on drum 70. The cams 71 effect inward movement of the crossheads 68 to strip the package from the pins, and the corresponding cam 72 returns the crosshead 68 to normal position after a package has been discharged. Expansible helical springs 73 are mounted upon the member 66 and subserve the purpose of bumpers to sustain the impact of the inward movement of the crossheads 68 and to assist materially in the initial return of the crossheads to normal position. The cams for one stripper are placed ahead of the other pair. The corresponding return cams 72 are similarly disposed. Consequently when the winding heads are stopped, a package is discharged from one head out of turn with the other head. This successive discharge obviates clogging and simplifies matters for the operator. A sprocket 74 is fast to an end portion of the shaft 75 upon which the drums 70 are mounted. A drive chain 76 connects the sprocket 74 with a sprocket 77 fast to the shaft 8. In this manner, the package ejecting mechanism derives motion from the shaft 8. A clutch member 78, mounted upon an end portion of the shaft 75 to rotate therewith, is normally urged into clutch engagement with the sprocket 74 by means of an expandable helical spring 79. A projection 80, on the clutch member 78, is normally engaged by the inclined or cam end of a lever 81, whereby to hold the shaft 75 out of gear during the action of the package ejecting mechanism. A pin 82, projecting laterally from the lower end of the lever 81, is adapted to ride upon a cam 83 carried by the drum 52. When the pin 82 rides upon the cam 83, the upper end of the lever 81 is moved to clear the projection 80 and at this time, the spring 79 moves the member 78 into clutch engagement with the sprocket 74, whereby the shaft 75 is rotated and the two cams 71, being one in advance of the other, move the crossheads 68 to successively eject the packages, the movement being of such duration as to carry the crossheads 68 inward and then return them to normal position and at this instant the pin 82 clears the cam 83, thereby permitting the lever 81 to assume a normal position, whereby the projection 80 rides upon its cam end and disconnects the clutch member 78 from the sprocket 74 thereby throwing the ejecting or stripper mechanism.

nism out of action. An expansible helical spring 84 normally holds the lever 81 in predetermined position.

The cutting mechanism is disposed between the last set of compressing and feed rolls A and the package former, and comprises a fixed cutter 85 and movable cutters 86, the latter being preferably pivoted. A bracket 87, secured to the table 4, supports the cutting mechanism. The cutters 86 operate between guides 88 and 89, the latter being disposed above the fixed cutter 85 and consisting of an L-bar, the horizontal wing of which is spaced from the cutter 85 to provide a passage for the tube. A plate 90, in line with the cutter 85, extends into the space formed between the rolls of the pair A and supports and gives proper direction to the tube on its way to the cutting mechanism. The cutter actuating mechanisms are duplicates of one another and a description of one will suffice as an explanation for both. A rod 91, connected with the outer end of the cutter 86, is pivoted at its lower end to an arm 92 which is fulcrumed at 93. A contractile helical spring 94 has connection at one end with the elements 91 and 92 at their pivot juncture and normally exerts a down pull on the outer end of the cutter 86. One of the arms 92 is extended, as indicated at 95, and is provided at its outer end with a lateral extension 96 disposed to ride upon a cam 97 fast to the shaft 47, whereby to hold the cutter 86 spaced from the cutter 85 to admit of the passage of the tube between the cutters to the package forming mechanism. The cam 97 is formed with a notch 98 which is so disposed as to effect operation of the cutting mechanism to sever the tube when a package has been formed. When the notch 98 registers with the lateral extension 96, the latter drops therein and admits of the cutter 86 operating by the action of the spring 94. The action of the cutting mechanism is momentary, the cutter 86 moving across the path of the tube and severing the same and instantly returning to normal position by the lateral extension 96 riding out of the notch 98 and engaging the circular face of the cam 97.

Just prior to this cutting movement the cam 53^a on the drum 53 actuates a lever 53^b, which lever controls a clutch 53^c through which the sprocket 51^a is driven (see Figures 4 and 11). As above described, the sprocket 51^a is connected by a drive chain 51 with the lower roll of the pair of feed rolls A so that the disengagement of the clutch 53^c immediately stops the forward movement of the tubing, since the sprocket 51^a is driven from the shaft 8 solely through this clutch mechanism. The forward movement of the tubing having now ceased, the winding heads no longer rotate, but the sprockets 57 slip on the sleeves 56^a. As soon as the severing

of the tubes is accomplished the heads again rotate to complete the winding of the severed tubes. The cams 52^a and 54^a then disengage the clutch members 59 to stop the winding heads and the packages are discharged successively from the heads by the action of the cams 71.

The disengagement of the clutch members 59, of course, brings the winding heads to a stop and they remain stationary until the leading end of the tubing is supplied by the feed rolls. The clutch members 59 are then again engaged and the winding continues until the clutch 56^c is actuated as above described, at which time the winding stops and the sprockets 57 again slip on the sleeve 56^a as above described. To prevent overthrow of the package former and insure the pins 62 occupying a relatively vertical position so that the end of the tube may pass therebetween preliminary to the next operation of the package forming mechanism, stop devices 99 and 100 are provided. The part 99 consists of a fixed rod attached to a convenient part of the machine, and the part 100 consists of a stop projecting outwardly from the clutch member 59. When the clutch member 59 is moved outwardly said stop 100 extends across the path of the part 99, thereby bringing the shaft 56 to rest in a predetermined position, that is, with the pins 62 the one above the other in vertical position, as indicated most clearly in Figure 6.

After the upper strip 21 has been threaded through the tube forming apparatus, and with the adhesive strip 22 has been carried through the feed rolls A, B and C, the machine is ready to operate. It is started up just after having been turned beyond the point where the strippers 68 have been actuated, at which time the winding heads are stationary with the pins 62 in vertical relation. The timing of the cams is such that the feed rolls are put in motion before the winding heads, and a strip of tubing is projected between the pins of each head from the feed rolls A before the heads commence to rotate. As they are rotated, the pins of each head wrap the projecting portion of the tube upon itself and commence to form a package of the form shown in my copending application Serial No. 535,643, filed February 10, 1922.

The wrapping of the tube continues for a period determined by the speed ratio of the winding shaft to the cam shaft, and it will be apparent that this speed ratio, together with the spacing of the pins 62, determines the size of the package which will be formed.

After a package has been formed, the winding head and the feed rolls stop as above set forth, while the movable knife 86 severs the tube. As soon as the tube is severed, the winding head again rotates to wind the

severed end portion of the tube on to the package. The stopping of the head for cutting naturally follows from the stopping of the feed rolls, since the head is driven through a friction clutch, and as soon as the load is relieved by the severing of the tube, the head immediately rotates until the positive clutch has been thrown out of engagement prior to the stripping of the completed package from the head.

It should be particularly noted that since the package is wound upon spaced apart members and takes a noncircular shape, the tubing, after it leaves the feed rolls A and before it reaches the package, is continuously oscillating. For this reason, the shearing knife is placed immediately adjacent the feed rolls A to prevent interference.

What is claimed is:

1. Package forming apparatus for strip material including a rotatable winding head having a pair of spaced apart members, means for projecting therebetween the end of the material to be wound whereby the end of the material will be held by the head on rotation thereof, means for rotating the head to wind the material upon itself and form a package, means for throwing the winding means out of operation after a predetermined period, and means for sliding the package endwise of the spaced apart members and laterally of the material supply.

2. Package forming apparatus for strip material including a rotatable winding head having a pair of spaced apart members, means for supplying material to the winding head, said means being adapted to project between the spaced apart members the end of the material to be wound, means for rotating the head to wind the material upon itself, means for severing the wound material from the supply means, and means for stripping the severed package from the spaced apart members.

3. Package forming apparatus for strip material including a rotatable winding head having a pair of spaced apart members, means for supplying material to the winding head, said means being effective for projecting between the spaced apart members the end of the material to be wound, means for rotating the head to wind the material upon itself and form a package, means for stopping the winding head after a predetermined period, means for severing the wound material from the supply means after the winding head has been stopped, and means for further rotating the winding head to wind the severed end portion of the material onto the package.

4. Package forming apparatus for strip material including a rotatable winding head having a pair of spaced apart members, supply means for feeding material to the winding head, means for rotating the head, means

for stopping the supply means, means for stopping the head with one of the spaced apart members on either side of the path of the material fed from the supply means, the supply means being adapted to project between the spaced apart members the end of the material to be wound, and means for throwing the supply means into operation before the winding head is rotated.

5. Package forming apparatus for strip material including a rotatable winding head having a pair of spaced apart members, supply means for feeding material to the winding head, means for rotating the head a predetermined period, means for severing the material, means for continuing the rotation of the head to wind the severed end portion of the material, means for stopping the head with one of the spaced apart members on either side of the path of the material fed from the supply means, means for stripping the package from the spaced apart members, and means for throwing the supply means into operation before rotation of the head, the supply means being adapted to project between the spaced apart members the end of the material to be wound.

6. Package forming apparatus for strip material including a rotatable winding head, means for supplying tubing thereto, means for rotating the head to wind the tubing upon itself and form a package, means for throwing the winding head out of operation, means for severing the tubing from the supply means, means for further rotating the winding head to wind the severed end portion of the tubing onto the package, and means for sliding the severed package laterally of the material supply to permit the starting of another package.

7. Package forming apparatus for strip material, including a fixed supply means, a rotatable winding head spaced therefrom, the head being adapted to form a non-circular package, whereby the material being wound and lying between the supply means and the winding head is vibrated laterally during the winding operation, and means for severing the material, the severing means being adjacent the supply means, whereby the severing occurs at a point where the vibration of the material is substantially a minimum.

8. Package forming apparatus for strip material including a rotatable winding head, means for supplying material thereto, means for rotating the winding head, and means for stopping the supply means after a predetermined period, the rotating means for the winding head being adapted to slip when the supply means is stopped and means for severing the material.

9. Package forming apparatus for strip material including a rotatable winding head, means for supplying material thereto,

means for rotating the winding head, means for stopping the supply means after a predetermined period, the rotating means for the winding head being adapted to slip when the supply means is stopped, and means for severing the material.

10. Package forming apparatus for strip material including a rotatable winding head adapted to form a non-circular package, means for supplying material thereto, means for rotating the winding head, means for stopping the supply means after a predetermined period, the rotating means for the winding head being adapted to slip when the supply means is stopped, and means adjacent the supply means for severing the material.

11. Package forming apparatus for strip material including a rotatable winding head, means for supplying material thereto, means for rotating the winding head, means for stopping the supply means after a predetermined period, and means spaced from the winding head for severing the material, the rotating means for the winding head being adapted to slip when the supply means is stopped and to wind the end of the strip material when the same is severed from the material supply.

12. Package forming apparatus for strip material including a plurality of winding heads, means for substantially simultaneously feeding material thereto, means for substantially simultaneously rotating the same to form a package on each head, means for substantially simultaneously stopping the feeding means, means for severing the material supply adjacent the feeding means, the heads being adapted to remain stationary from the time the feeding means is

stopped until the material is severed, and also being adapted to wind the severed end portions onto the package, and means for successively discharging the packages from the heads.

13. Package forming apparatus for strip material including a pair of oppositely disposed winding heads, feeding means adapted to supply material to both heads, means for rotating the heads, means for stopping the feeding means after a predetermined time, and means for successively discharging the packages toward a common point between the heads.

14. Package forming apparatus for strip material including a pair of oppositely disposed winding heads, feeding means adapted to supply material to both heads, means for rotating the heads, means for stopping the feeding means after a predetermined time, means for severing the packaged material from the material supply, the heads being adapted to wind the severed end portions of the material onto the package, and means for successively discharging the packages toward a common point between the heads.

15. Package forming apparatus for strip material including a pair of oppositely disposed winding heads, feeding means adapted to supply material to both heads, means for rotating the heads, means for stopping the feeding means after a predetermined time, and means for successively discharging the packages toward a common point between the heads, the winding heads being frictionally driven.

In testimony whereof I affix my signature.

GEORGE SHERMAN CLARK.
